(12) **United States Design Patent** (10) **Patent No.:** **US D795,855 S**
(45) **Date of Patent:** **** Aug. 29, 2017**

(54) **PORTABLE ELECTRONIC DEVICE**

- (71) Applicant: **Samsung Electronics Co., Ltd.**, Suwon-si (KR)
- (72) Inventors: **Namsu Kim**, Seoul (KR); **Dohyung Ha**, Gwangmyeong-si (KR); **Saehee Lee**, Incheon (KR); **Hyunsook Kim**, Seoul (KR)
- (73) Assignee: **Samsung Electronics Co., Ltd.**, Suwon-si (KR)
- (**) Term: **14 Years**
- (21) Appl. No.: **29/514,055**
- (22) Filed: **Jan. 8, 2015**

Related U.S. Application Data

- (63) Continuation-in-part of application No. 29/504,706, filed on Oct. 8, 2014, which is a continuation-in-part of application No. 29/504,002, filed on Oct. 1, 2014, now Pat. No. Des. 779,449.

CLAIM

We claim the ornamental design for a portable electronic device, as shown and described.

DESCRIPTION

FIG. 1 is a front perspective view of a portable electronic device showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof; and,
FIG. 8 is another perspective view thereof.

The short dash-dash broken lines in the figures show portions of the portable electronic device which form no part of the claimed design.

The dot-dash broken lines in the figures represent an unclaimed boundary line and form no part of the claimed design.
